METHOD OF AND MACHINE FOR APPLYING
REINFORCING STRIP MATERIALRobert A. Hartt, Lynn, Mass., assignor, by mesne
assignments, to Griess, Pfeifer & Company,
Inc., Cincinnati, Ohio, a corporation of Ohio

Application June 3, 1930, Serial No. 459,066

2 Claims. (Cl. 12—55)

It is a common practice to apply reenforcing tapes, bindings and similar strip material to various kinds of articles and particularly to shoes and other footwear, hereinafter referred to collectively as "shoes". In some cases the reenforcing strips are secured flatwise, either by adhesives or stitching or both, while in other instances, as in edge binding, the reenforcing material is folded over the edge of the shoe upper or other part of the work to which it is applied. Frequently these bindings and strip materials are used solely for ornamental purposes.

The present invention relates to methods of and machines for applying reenforcing strip material and is more especially concerned with those reenforcing tapes, bindings and the like which are coated with a meltable adhesive. In applying reinforcements of this kind it is necessary to heat the adhesive coating sufficiently to make it tacky and thus to cause it to adhere firmly to the parts to be reinforced. This has been done heretofore by running the reenforcing strip in contact with heated hammers, hot pressing devices or the like. The use of such devices, however, complicates the construction of the machines in which the operation of applying the reenforcing strip material is performed, and frequently they interfere with the handling of the work. Furthermore, it is difficult to incorporate such devices in some machines in any practical manner. To avoid these difficulties and to facilitate the application and handling of reenforcing material carrying meltable adhesives constitutes the chief object of this invention.

The nature of the invention will be readily understood from the following description when read in connection with the accompanying drawings, and the novel features will be particularly pointed out in the appended claims.

40 In the drawings:

Fig. 1 is a perspective view of a folding machine of a common commercial type equipped with apparatus constructed in accordance with this invention;

45 Fig. 2 is a perspective view showing those parts of the machine which perform the folding operation;

Figs. 3 and 4 are perspective views, partly in cross section, illustrating steps of the present method; and

50 Fig. 5 is a front elevation, partly in cross section showing certain details of the construction illustrated in Fig. 1.

The drawings show the invention applied to 55 a rotary folding machine of a common commer-

cial construction. It is designed especially for applying edge binding to the uppers of shoes and to other kinds of work which can be handled in essentially the same manner. The usual practice is to stitch the binding or reenforcing strip 2 (Fig. 3) to the edge of the part 3 of the upper or equivalent article of work, and later to fold the free portion of the binding over the edge 4 of the upper and to press it down upon the margin of the upper in the manner illustrated in Figs. 10 3 and 4.

The machine shown includes a driven feed wheel 5 which serves both to support and feed the work, and a rotary head 6 carrying a series of folding disks 7 which not only revolve with the head, but are also positively rotated on their own axes. A guide block 8 best shown in Fig. 2, is positioned adjacent to the wheel 5 and head 6 and has an angular guiding face 9 across which the work is fed on its way to the folding disks. As the work 15 travels across the guide block 8, it is pressed against the guiding face 9 by a small roll or wheel 10 having a toothed edge, the wheel being supported for yielding movement toward and from the guide block. The block thus serves both as 20 a support for the binding and also as one element of the folding means. It will be observed that the axis of the rotary head 6 is inclined with reference to the feed wheel 5. The arrangement is such that as the work is fed across the 25 guide block 8, the binding 2 is bent or folded upwardly at approximately right angles to and across the edge of the section 3 of the shoe upper, and as the binding passes out of engagement with the upright guiding surface of the block 30 35 8, it is engaged by the disks 7 which wipes it forward over the margin of the upper 3 and presses it down into the position shown in Fig. 4. These steps in the folding operation are performed progressively as the work is fed past the folding 40 instrumentalities.

The machine so far described is substantially as it has been used heretofore.

When a binding is used which is coated with a meltable adhesive, the coating is applied to that 45 surface of the binding strip which will be folded inwardly and pressed against the margin of the section 3 of the shoe upper. The binding is preferably sewed to the edge of the upper exactly as has been the custom heretofore. This invention provides an apparatus for directing a current of hot air or other suitable gaseous fluid against the adhesive coating of the binding just before it is folded over, the hot air or other fluid serving to soften the adhesive sufficiently to make 50 55

it tacky and cause it to adhere firmly to the margin of the upper 3.

The apparatus illustrated for performing this function comprises an electric heating unit 12 mounted in a casing 13 having a chamber 14 considerably larger than the unit, so that ample air space is provided around the unit. This casing is supported by a bracket 15 (Fig. 1) secured to the frame of the machine. Suitable piping, 10 including a pipe or tube 16, conducts air from a blower or pump 17 into the chamber 14, the pump or blower being driven by a motor 18. Additional connections, including a curved tube 19, conduct air from the chamber 14 and direct it 15 against the coated surface *a* (Fig. 3) of the binding 2, the discharge end of this tube being shaped to form a nozzle as indicated at 20 (Fig. 5). Preferably the pipe connections include a valve 21 adjustable to enable the operator to regulate 20 the flow of air to suit the requirement of the work.

As the air is forced through the chamber 14, it becomes heated to a relatively high degree, such, for example, as 160 or 170° F., and it is discharged against the adhesive coating *a* at only 25 a slightly lower temperature. This coating thereupon becomes tacky, and immediately thereafter the part of the binding bearing the tacky adhesive is folded over the edge and pressed down upon the margin of the section 3 of the 30 upper and adheres firmly to this part of the work. It is preferable to position the nozzle approximately as indicated in Fig. 5 so that the air will be directed along the coated surface longitudinally of the binding strip and toward the 35 folding devices, or in other words, in the direction in which the binding is being fed.

In using an apparatus of this character, considerable flexibility in organization is permitted by the fact that the heating medium which acts 40 on the adhesive coating is of a gaseous nature. Because of this fact the heating element need not be located in any particular relationship to the operating elements of the machine, and the discharge pipe or tube can be bent or arranged in 45 such a manner as to avoid interference with the work or with the movements of the operator. While it is preferable to direct the blast or hot air or other fluid against the coating at a point fairly close to the position at which the folding 50 operation is being performed, considerable latitude in this respect is permitted particularly since the temperature of the fluid can be varied as required. The necessity for a fixed and accurate relationship between the path of travel of the 55 work and the heating element which is to act on it, therefore, are avoided, and the application of the heating apparatus to existing machines is facilitated.

While it is usually preferable to use air as the fluid medium and to heat the air by electrical apparatus, it is contemplated that other fluids, such, for example, as steam can be used, and that other methods of heating can be employed. The 5 practice in these respects will be determined largely by the conditions surrounding individual installations, the nature of the adhesive coating and other practical conditions. These factors also will determine the temperature of the 10 heating medium used.

While I have herein shown and described a typical apparatus embodying this invention, and have described the method of this invention in connection with it, it will be understood that 15 the method may be practiced with the aid of a wide variety of forms of apparatus, and that the invention may be embodied in other forms without departing from the spirit and scope thereof. Also, that while the invention has been 20 shown in connection with a specific machine, this showing has been made rather by way of illustration than limitation, and the invention is equally applicable to other machines for applying reinforcing tapes and bindings.

It will be understood that the term "meltable adhesives" refers to that class of adhesives which are melted or softened by heat in applying them to the articles to which they are to adhere. Usually such adhesives are relatively insoluble in 25 water.

Having thus described my invention, what I desire to claim as new is:

1. That improvement in methods of securing a reenforcing strip of sheet material coated with 35 a meltable adhesive to an article of work which consists in relatively feeding said article and strip, pressing said strip against said article with the adhesive coating in contact with the article, and rendering the adhesive tacky immediately 40 prior to bringing it into contact with said article by blowing a hot gaseous fluid along the surface of said adhesive coating longitudinally of said strip.

2. In a machine for folding a strip of edge 45 binding material coated with a meltable adhesive about the edge of a shoe upper, or the like, comprising, in combination, folding devices for acting on said strip to fold it across the edge and to press it down upon the margin of the upper, 50 means for feeding the work past said devices, and means for directing a current of hot gaseous fluid along the surface of the adhesive coating on said binding longitudinally of said strip while the work is being so fed to render said coating tacky 55 preparatory to being pressed against the margin of the upper by said devices.

ROBERT A. HARTT.
